UNITED STATES PATENT OFFICE

2,472,867

HYDRAULIC JACK

Herbert A. Thorndike, Oshkosh, Wis., assignor,
by mesne assignments, to Vulcan Manufacturing Co., Inc., Winona, Minn.

Application June 20, 1946, Serial No. 678,048

3 Claims. (Cl. 103—228)

1

This invention relates to new and useful improvements in hydraulic pumps, and more particularly to a hydraulic pump of the reciprocating type having an improved check valve assembly.

The hydraulic pump which forms the subject matter of this invention is particularly designed for use in a hydraulic jack, such as that described in my copending applications Serial Nos. 787,080 and 928.

The check valve assembly of hydraulic jack pumps is an especially critical unit, and any foreign matter in the fluid tends to accumulate around the valve seats, seriously interfering with the operation of the pump. Frequently such jacks are employed for general farm use, and farmers are in the habit of adding any available fluid to the system when the need arises, even using engine crankcase drainings. Hence it is obvious that the check valve assembly in the pump of a hydraulic jack must be readily accessible for frequent cleaning.

It is therefore an object of this invention to provide a compact hydraulic pump, especially adaptable for use with a jack, which may easily be disassembled for cleaning with only a few ordinary tools.

A further object of this invention is the provision of a unitary valve assembly for a reciprocating type of hydraulic pump which can be removed from the pump for cleaning or replacement by merely removing the pump cylinder.

Still another object of this invention is to provide a unitary valve assembly for a hydraulic pump which may be cheaply and easily constructed, and which will serve as the end wall of the pump cylinder and also as a gland to afford a fluid tight seal in the cylinder.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a view in elevation of a hydraulic

5 jack having the pump of this invention incorporated therein;

Figure 2 is a horizontal section of the jack along the line 2—2 in Figure 1;

Figure 3 is a vertical section through the jack along the line 3—3 in Figure 2;

Figure 4 is a perspective view of the valve assembly of this invention, partially sectioned; and

Figure 5 is a vertical section through the check valve assembly along the line 5—5 in Figure 4.

Referring now more particularly to the accompanying drawings in which like numerals designate like parts throughout the several views, the numeral 1 designates the base of a hydraulic jack into which is received a tubular fluid reservoir 2. Mounted in the reservoir is a jack cylinder 3 (see Figure 2) in which a jack ram 4 is slidably carried.

20 A pump cylinder, comprising a tubular member 5, having a thread 6 at its base, is received in a well 7 in the jack base (see Figure 3). A pump piston 8 is reciprocable with the pump cylinder by means of a pump handle 9 which is fulcrumed at a pivot 10 carried by a link rod 11.

25 Passages 12 and 13 in the pump base open to the bottom of the well, and communicate with the fluid reservoir 2 and the jack cylinder 3, respectively. These passages are drilled into the

30 base from one side thereof, and have their outer ends closed by plug screws 14. Removal of the plug screws gives access to tubular screen filters 15 set in the passages at the point 16 where the mouths of the passages open into the bottom of the well 7, and permits the filters to be withdrawn from the passages for cleaning.

35 Set into the well 7 is a unitary check valve assembly 17. The valve cage comprises a cylindrical body or plug 17' (see Figure 4) preferably formed from bar stock and of such diameter as to be snugly received in the well, and through which a pair of ports 18 and 19 are bored parallel with the axis of the plug. Complementary but oppositely acting check valves are installed 40 in these ports. Each of the ports has a counterbore 20, the shoulder of which 21 forms a seat for a ball valve 22, and threaded tubular spring seats 23 center compression springs 24 which yieldingly urge the balls against their seats.

45 The ports in the valve plug 17' are positioned to align with the ends of the passages 12 and 13 when the valve plug is set into the well. The centers of the ports are radially equi-distant from the axis of the plug, so that the plug may be 50 inserted with either end downward. A third bore

55

25 extends through the plug parallel to and equidistant from the ports 18 and 19 and a pin 26, anchored in the bottom of the well, extends into the bore 25 to locate the plug and align its ports with the passages 12 and 13.

A gasket 27 (see Figure 3), of neoprene or other suitable flexible material, shaped to match an end of the plug 17', is interposed between the plug and the bottom of the well. As the tubular cylinder member 5 is threaded into the top of the well, the bottom of the cylinder member bears upon the top of the plug, pressing it down upon the gasket, which, in turn, expands horizontally against the cylindrical walls of the well to form a fluid tight seal.

Disassembly of the entire pump may thus be accomplished by unscrewing the tubular cylinder member and lifting the valve plug out of the well. By removing the plug screws which close the ends of the fluid passages, the filter screens may be removed and access may be had to the entire length of the fluid passages for cleaning them.

From the foregoing description, taken in connection with the accompanying drawings, it will readily be seen that this invention provides a reciprocating type of hydraulic pump of simplified construction, particularly suited for use with a hydraulic jack.

What I claim as my invention is:

1. In a reciprocating type hydraulic pump: a body having a bore open at one end and closed at the other, and having inlet and outlet passages opening to the bore through its closed end; a cylindrical plug, of a size to fit freely into said bore, received therein, said plug having parallel ends and having inlet and outlet ports extending axially therethrough, the spacing of said ports being such as to align with the mouths of the inlet and outlet passages in the closed end of the bore; oppositely acting check valves in said ports; means for removably securing said plug in position; and means engageable between the closed end of the bore and either end of the plug for properly locating the same for alignment between its ports and the mouths of the inlet and outlet passages so that said plug may be inserted with either end innermost.

2. In a reciprocating type hydraulic pump, a body having a well and having fluid inlet and out-

let passages in open communication with the bottom of the well, said passages also extending to a side wall of the body; a unitary valve assembly removably received in the bottom of said well, said valve assembly having intake and discharge ports extending axially therethrough and oppositely acting check valves in said ports; means for locating said valve assembly in the well with its intake and discharge ports aligned with said inlet and outlet passages; a tubular member secured to the body over the mouth of the well with a part thereof engaging the valve assembly to hold the same in place, said tubular member constituting the cylinder of the pump so that fluid is drawn through the inlet passage and the intake port to enter the cylinder and is expelled from the cylinder through the discharge port and outlet passage; filters in said inlet and outlet passages at their points of communication with the bottom of the well, said filters being removable from the passages through the ends thereof which extend to a side wall of the body; and removable means for closing the open ends of said passages.

25 3. As an article of manufacture, a self contained intake and discharge valve unit adapted for removable insertion into a valve chamber, comprising: a cylindrical plug having identical ends and intake and discharge passages extending axially therethrough at equi-spaced radial distances from the axis of the plug; oppositely acting check valves in said passages; and eccentrically disposed locating means on the plug adapted to cooperate with other means in the 30 valve chamber for properly locating the plug in the valve chamber with either end thereof innermost.
